(57) **CLAIM**

The ornamental design for a shoe as shown and described.

DESCRIPTION

FIG. 1 is a bottom front perspective view of a shoe showing my new design;

FIG. 2 is a bottom view thereof;

FIG. 3 is a bottom rear perspective view thereof; and,

FIG. 4 is an enlarged view of the claim as shown in FIG. 1 with environment removed for clarity purposes.

The broken lines immediately adjacent to the shaded area define the bounds of the claimed design and form no part thereof. The broken lines showing the seven circular shaped regions and the three triangular shaped regions form no part of the claimed design. The broken lines depicting the remainder of the shoe form no part of the claimed design.
